Primary Examiner — Bridget L Eland*(74) Attorney, Agent, or Firm* — McAndrews Held & Malloy, Ltd.(57) **CLAIM**

The ornamental design for a router, as shown and described.

DESCRIPTION

FIG. 1 is a front perspective view of a router showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is an enlarged view of the portion 8 encircled in FIG. 1;

FIG. 9 is an enlarged view of the portion 9 encircled in FIG. 1;

FIG. 10 is an enlarged view of the portion 10 encircled in FIG. 3; and,

FIG. 11 is an enlarged view of the portion 11 encircled in FIG. 6.

The dashed broken lines in the figures illustrate portions of the router that form no part of the claimed design.

The dot-dot-dash broken lines in the drawings encircling portions of the claimed design that are illustrated in enlargements form no part of the claimed design.

1 Claim, 10 Drawing Sheets(56)
